FEED DOG RECUTTING FIXTURE

Leonard C. Corcoran, Cleveland Heights, Ohio

Application June 18, 1935, Serial No. 27,218

4 Claims. (Cl. 29—76)

The present invention relates to a fixture for recutting, resurfacing, and salvaging used sewing machine feed dogs. The general object and nature of my invention is to provide a device adapted to hold all sizes, shapes and types of sewing machine feed dogs, together with means for guiding a recutting tool, such as a file, whereby the damaged and worn teeth of such feed dogs may be accurately and quickly recut and placed in a serviceable condition.

A further object of the invention is to provide such a feed dog recutting fixture which is of simplified construction and of a portable nature whereby the fixture can be carried about in the repair man's tool box and clamped in an ordinary bench vise during use. Additional objects and advantages of the invention shall become apparent as the following description proceeds.

To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

30 Fig. 1 is a perspective view of the fixture embodying the principle of my invention; Fig. 2 is a top plan view of the device shown in Fig. 1; Fig. 3 is a side elevational view partially in section, the sectioned portion being taken substantially along the line 3—3 of Fig. 2; and Fig. 4 is a perspective view of a legless type of feed dog adapted to be serviced by my fixture.

Since a feed dog is an element of a sewing machine which is particularly subject to damage and wear, due to the fact that it grips and releases the material being sewed each time a stitch is taken, it is of utmost importance that the gripping teeth of such a feed dog be maintained in an efficient and serviceable condition. The efficiency of operation of the entire sewing machine mechanism is dependent upon the ability of the feed dog to properly grip and advance the material at each stitch. The fixture of my invention which has been designed for the purpose of recutting and maintaining the proper condition of sewing machine feed dog teeth, consists essentially of a pair of guides for supporting the reciprocal movement of a cutting tool such as a triangular file, and a work holding block movable with respect to such guides whereby the position

of a feed dog carried by such block may be adjusted and the cutting operation may be properly aligned and gauged.

Referring more particularly to the drawing, my fixture consists of a rectangular base block 1 having parallel sides 2 whereby the fixture may be clamped and held in an ordinary bench vise (not shown). Four posts 3 positioned adjacent the four corners of the base block 1 carry the hardened steel bars or file guides 4. A work holding block 5 is movably supported with respect to the base block 1 by means of the two pins 6 fixed to the block 5 and slideable through holes drilled in the base block 1. The pins 6 serve as means for maintaining and accurately guiding the movable block 5 with respect to the base block 1 and the file guides 4. A threaded shaft 7 threadably engages the base block 1 as at 8 and is locked against longitudinal movement in the work holding block 5 by means of the pointed set screw 9 whose end engages in a V-shaped annular groove in the end of the threaded shaft 7. A wing handle 11 is fixed to the outer end of the shaft 7 and serves as means for facilitating the manual rotation thereof. A wing nut 11' threadably engages the shaft 7 and is adapted to bear against the bottom side of the base block 1 for locking the shaft 7 against rotation and thereby holding the movable work holding block 5 in desired position.

30 A feed dog 15 of the projecting leg type, and having a series of teeth 16 is adapted to be mounted upon the work holding block 5. Such mounting is accomplished by means of a slot or channel 17 in the side face of the block 5, in which the leg 18 of the feed dog 15 closely fits. A stud 19 passes through the opening 20 in the feed dog leg 18 and threadably engages the tapped hole 21 in the work holding block 5. Additional slots of wider dimensions, such as the slot 17' may be provided in order to accommodate feed dogs having legs of different widths.

Legless feed dogs such as the feed dog 25 shown in Fig. 4 are mounted on the top surface of the work holding block 5 by means of suitable screws 45 or studs passing through the holes 26 in the feed dog and engaged in the tapped holes 27 in the block 5. A triangular file 30 having rounded ends 31 and 32 constitutes the cutting tool. The end portions 31 and 32 of the file are adapted to bear against and be guided by the parallel guide bars 4. The intermediate portion of the file 30 bears against the surfaces of the feed dog teeth 16 (as best shown in Fig. 3) and recuts them to accurate and desired form.

50

55

In operation, the damaged feed dog is removed from the sewing machine, annealed in order to soften the metal therein, mounted upon the work holding block 5 and the latter is adjusted to such a position with respect to the file guides 4 where-by the necessary depth of cut will result. The alignment and uniformity of the recutting operation of the feed dog teeth 16 may be inspected and checked from time to time by moving the block 15 and sighting across the top of the parallel file guides 4. After the recutting operation, the feed dog may be reinstated to its previous case hardened condition by a simple cyanide bath treatment.

15 The above described fixture permits the recutting and salvaging of damaged and worn sewing machine feed dogs which heretofore have been completely discarded and replaced by new ones. The fixture may be conveniently carried about 20 from place to place by the repair man, and easily mounted in an ordinary vise, or can even be held by hand. It will also be seen that my above-described fixture is of universal application, and will accommodate practically all sizes, types and 25 shapes of sewing machine feed dogs.

Other modes of applying the principle of my invention may be employed instead of the one explained, change being made as regards the mechanism herein disclosed, provided the means 30 stated by any of the following claims or the equivalent of such stated means be employed.

I therefore particularly point out and distinctly claim as my invention:—

1. In a sewing machine feed dog recutting fixture, the combination of a base block having parallel side faces adapted to be gripped by an ordinary vise, file guides carried in spaced relationship with respect to said block, and a work holding block movable with respect to said guides, 40 said work holding block having a flat upper surface for the attachment of legless feed dogs, and also having slots in its side faces for the attachment of feed dogs with extending legs.

2. In a sewing machine feed dog recutting fixture, the combination of a base block having parallel side faces adapted to be gripped by an or- 45

dinary vise, parallel hardened bars carried in spaced relationship with respect to said block, said bars being adapted to guide the reciprocal movement of a filing tool, a work holding block adapted to hold feed dogs in a position with their teeth parallel to said guides, said work holding block having a flat upper surface for the attachment of legless feed dogs and also having slots in its side faces for the attachment of feed dogs with extending legs, a rotatable shaft located 10 to said work holding block and threadably engaging said base block, and a lock nut on said shaft for locking the latter against rotation to said base block.

3. In a sewing machine feed dog recutting fixture, the combination of a base block having parallel side faces adapted to be gripped by an ordinary vise, file guides carried in spaced relationship with respect to said block, a work holding block movable with respect to said guides, 20 said work holding block being adapted to hold feed dogs in a position with their teeth parallel to said guide, and guide pins carried by said work holding block and slidably positioned in said base block.

4. In a sewing machine feed dog recutting fixture, the combination of a base block having parallel side faces adapted to be gripped by an ordinary vise, parallel hardened bars carried in spaced relationship with respect to said block, 30 said bars being adapted to guide the reciprocal movement of a filing tool, a work holding block adapted to hold feed dogs in a position with their teeth parallel to said guides, said work holding block having a flat upper surface for the attachment of legless feed dogs and also having slots in its side faces for the attachment of feed dogs with extending legs, a rotatable shaft located to said work holding block and threadably engaging said base block, a lock nut on said shaft 40 for locking the latter against rotation to said base block, and guide pins carried by said work holding block and slidably positioned in said block.
